UNITED STATES PATENT OFFICE.

GORDON B. POLLOCK, OF HOLLYWOOD, CALIFORNIA.

BRACKET.

Application filed September 11, 1923. Serial No. 662,058.

To all whom it may concern:

Be it known that I, GORDON B. POLLOCK, a citizen of the United States, residing at Hollywood, Los Angeles, county of Los Angeles, and State of California, have invented a new and useful Bracket, of which the following is a specification.

This invention relates to a bracket primarily intended for suspending and sealing a dispenser of the type commonly employed for holding and delivering paste and creams such as tooth paste, shaving cream and the like, although various other forms of containers or dispensers may be employed therewith.

Heretofore, much annoyance and inconvenience to the user of such dispensers has occurred from a tendency of the caps employed therewith to become misplaced whereafter the dispenser cannot be properly sealed from the elements and partial drying of the materials therein, with a corresponding change in their properties, takes place. Moreover, the loss of the cap will result in the contents of the dispenser being accidentally expelled therefrom with considerable annoyance to the user.

An object of this invention is to provide a form of bracket which may be used for supporting and suspending such dispenser and holding the same sealed from the elements so that the loss or misplacement of the cap will not result in the disadvantages heretofore referred to and so that use of such dispensers and the contents thereof may be greatly facilitated.

Another object of this invention is to provide a form of bracket which may be substituted for the cap normally provided with such a dispenser and which will support the dispenser and hold the same pressed against a closure member provided by the bracket and further to provide such a form of bracket which may be readily engaged and released from the dispenser.

Another object of the invention is to provide a new form of cap for a container or dispenser which cap can be more readily attached to the container or dispenser than the screw form of caps customarily employed.

Other objects and advantages of this invention will be apparent from a description of the accompanying drawings wherein there is illustrated a number of examples or embodiments of the invention.

In the drawings:

Figure 1 is an elevation of one embodiment of the invention illustrating a tube form of dispenser and a brush supported by the bracket.

Fig. 2 is a longitudinal vertical section of the bracket shown in Fig. 1 with the dispenser and brush removed.

Fig. 3 is a bottom view of Fig. 2.

Figs. 4 and 5 refer to a modified form of the invention, in which

Fig. 4 is a longitudinal vertical section and

Fig. 5 is an inverted view of Fig. 4.

Figs. 6 and 7 refer to a further embodiment of the invention, in which

Fig. 6 is a longitudinal vertical section and

Fig. 7 is an inverted view of Fig. 6.

In the drawings, first referring to the embodiment shown in Figs. 1 to 3 inclusive, the bracket is intended to support and seal such dispensers, as generally indicated by

1, which are provided with a neck 2 from which the contents of the dispenser are delivered through an opening at the top of said neck 2. The bracket comprises a closure 3 which is cap-shaped in form and

adapted to fit over a portion of the neck 2 of said dispenser 1. Preferably within the closure 3 is provided packing material, indicated at 4, which may be of cork or other similar material. Said closure 3 is rigid

with and preferably forms an integral part of an arm 5 which is preferably disposed in substantially a horizontal plane. Means are provided for supporting the arm 5 and thereby the closure 3. In this embodiment

of the invention said means comprise a substantially vertical plate 6 integral with the arm 5 and extending downwardly from one end thereof. Said plate 6 is attached to a support such as the standard 7 by means of

screw 8. To preserve the customary cap of the dispenser 1, a section of the arm is pressed upward to form a threaded knob 9 to which the cap 16 of the dispenser 1 is secured.

Means are provided by the bracket for engaging said dispenser 1 and holding or pressing same against the closure 3, said means comprising grippers 10 and 11, the gripper 10 extending from the lower end of the plate 6 to a position slightly below

the closure 3 of the bracket, where the gripper is provided with an opening 12 of

- somewhat larger diameter than the neck 2 of the dispenser which is to be supported by the bracket. The gripper 11 extends from one end of the arm 5 to a position below the gripper 10 whereat the gripper is provided with an opening 13 of substantially the same size as the opening 12 in the gripper 10. Said openings 12 and 13 are normally maintained slightly staggered or eccentric. A hook 14 extends from the arm 5 and may be used to support a brush as indicated in Fig. 1. In this embodiment of the invention all of the component parts of the bracket are formed of spring metal.
- 15 In operation the cap of the dispenser 1 is first removed and secured to the knob 9. To engage the bracket with the dispenser pressure is applied to the arm 5 or closure 3 to press the same down, thereby the openings 12 and 13 of the gripper members will be aligned. The dispenser 1 is then inserted through the openings 12 and 13 and up with the top of the neck 2 extending into the closure 3 and engaging the packing material 4. On release of the pressure applied to the arm 5 or closure 3 the grippers 10 and 11 will again tend to assume the position indicated in Fig. 2 whereat the openings 12 and 13 are eccentric. The walls of the said openings thereby tend to close in on the neck 2 of the dispenser and thus grip and suspend the dispenser from the bracket. To release the dispenser from the bracket a pressure is applied on the arm 5 or closure 3.
- 20 In the embodiment of the invention shown in Figs. 4 and 5 a closure 3^a is provided, similar in construction and form to the closure 3 shown in Figs. 1 to 3 inclusive, said closure having cork or other packing material supported within it as indicated at 4^a. The bracket is formed in substantially one piece with an arm 5^a extending horizontally from the closure 3^a and bent vertically downward at its end to provide a vertical section 6^a, which in this embodiment of the invention is provided with a slot, through which screw 8 is passed to support the same. From the lower end of the section 6^a the bracket extends outwardly in the direction of the arm 5^a to provide a gripper arm 10^a below the closure 3^a formed on the arm 5^a. Said gripper arm 10^a is formed to provide receiving slot 17 of a size adapted to fit between threads or other protuberances on the neck 2 of the dispenser 1, the arm 10^a being disposed a less distance from the arm 5^a of the bracket than the length of the neck 2 of the dispenser. The free end of the arm 5^a may be reduced and turned up to form a hook such as indicated at 14^a when it is desired to hold or support a brush from the bracket.
- 25 With this form of bracket the dispenser 1 is inserted into the way 17 of the gripper arm 10^a and the arm 10^a pressed downward to permit the neck 2 of the dispenser to pass into the closure 3^a of the bracket whereupon on release of the gripper arm 10^a the dispenser will be pressed upward against the packing material 4^a and the dispenser thus supported and sealed from the elements.
- 30 In the embodiment shown in Figs. 6 and 7 the bracket is provided with a closure 3^b of a size to fit over the neck 2 of the dispenser 1. Said closure 3^b is preferably integral with an arm 5^b which extends horizontally from the closure and is bent downwardly at one end to provide a vertical section 6^b by which the bracket may be supported from a standard or other object by means of screws such as 8^b. From the lower end of the section 6^b the bracket extends outwardly and upwardly as indicated at 18 and engages the arm 5^b to provide a brace for the same. Below the closure 3^b is provided a gripper 10^b which in this embodiment of the invention is formed by a coil of spring metal, the opposite ends 19 of which extend outwardly from the bracket. Said gripper 10^b is supported in a housing 20 fixed to the arm 5^b below the closure 3^b. The gripper member 10^b is of a smaller diameter than the diameter of the neck 2 of the dispenser to be suspended by the bracket.
- 35 To engage the dispenser with the bracket the ends 19 of the gripper 10^b are pressed together which will cause the diameter of the gripper member 10^b to be somewhat enlarged, whereupon the dispenser is inserted through the gripper 10^b until it engages in the closure 3^b. Upon release the ends 19 of gripper 10^b will contract about the neck 2 of the dispenser and hold the same against the closure 3^b, thus suspending and sealing the dispenser.
- 40 While I have shown a number of embodiments this invention may take and have illustrated the preferred form of the invention, it is understood that the invention may be embodied in numerous other forms without departing from the spirit of the invention. This invention is of the scope set forth in the appended claims.
- 45 I claim:
1. A bracket of the class described comprising an arm providing a cap-shaped closure provided with packing means, a resilient gripper arm extending below the closure, and gripping edges provided by the first mentioned arm and resilient gripper respectively, said gripping edges being normally yieldingly held out of alignment and adapted, by pressure upon said first mentioned arm, to be brought into alignment.
  2. A bracket for suspending and sealing a dispenser having a reduced neck providing an outlet for the dispenser, which bracket includes an arm providing a cap-

shaped closure for the dispenser, a resilient gripper arm extending adjacent the lower end of the closure and having a gripping edge, and a gripping edge provided by said

5 first arm and normally resiliently urged towards a gripping position out of alignment with the other gripping edge, said two gripping edges being so related as to be brought into alignment by pressure exerted upon said bracket.

3. A bracket for suspending and sealing a dispenser having a reduced neck providing an outlet, which bracket embodies an arm having a cap-shaped closure for the 15 dispenser, a resilient gripper extending below the cap shaped closure, said gripper being provided with an opening below said cap-shaped closure and yieldingly maintained out of alignment therewith, means

carried by said arm providing a second opening below said cap-shaped closure, said openings and cap-shaped closure being adapted to be registered by pressure upon the arm, and means for supporting the bracket.

4. In a bracket of the class described, two arms having gripping edges, means for supporting the arms from spaced points about which the arms are adapted to flex, the arms extending therefrom into a cooperating position and being operative by flexing about their spaced points of support to assume both gripping and non-gripping positions, one of the arms also serving as a closure member.

Signed at Los Angeles, California, this 4th day of September, 1923.

GORDON B. POLLOCK.
